(57) **CLAIM**

The ornamental design for a lighting fixture, as shown and described.

DESCRIPTION

FIG. 1 is a perspective view of a lighting fixture in accordance with the new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a bottom view thereof; and,

FIG. 7 is a perspective view of the lighting fixture shown in FIGS. 1-6 configured as a wall sconce.

The broken lines in the figures are for illustrative purposes only and form no part of the claimed design.
